RACK FOR CANS

Thomas Nelson Elliott, Blackstone, Va.

Application August 29, 1947, Serial No. 771,325

2 Claims. (Cl. 248—147)

1

This invention relates to racks for holding cans of that type used in the disposal of garbage, trash and the like.

For many years, the use of cans for holding garbage and trash has proven a nuisance and an expense both to the housewife and those municipal agencies having the responsibility of collecting the garbage and trash and of sanitation. Such cans are frequently roughly handled, and the can, particularly the lid portion, becomes dented and no longer may be properly closed.

When this occurs and the cans are overturned by dogs, cats, and frequently children, the lids are lost, and a health menace is created by the garbage attracting mice and rats and spreading the germs. It is estimated that approximately eighty per cent of such can lids are lost in this manner shortly after the cans are placed in use.

In an effort to solve this problem, many devices have been made. A number of these have taken the form of racks to hold the cans to prevent their displacement or overturning. For various reasons these have not proven sufficiently practical to gain acceptance by the general public.

The object of the present invention is to provide a rack for garbage cans and the like which will be sufficiently rugged to withstand rough handling, and at the same time capable of operation with sufficient ease to be managed by the housewife and to speed the job of the collector.

Another object of the invention is to provide a rack for cans, in which the can lid becomes a part of the rack and is braced thereby to prevent its easy deformation.

A further object is to provide means to guide the lid to closed position so that it will not strike the can and be damaged thereby.

Still another object is to provide means to support the can lid in raised position during the placing of garbage in the can or the removal of the can from the rack so that the lid will not fall upon the can or against the rack.

A still further object of the invention is to provide a rack in which the can is snugly held, yet is readily removable without danger of striking the rack or the handles of the can becoming caught on part of the rack structure.

Yet another object is the provision of a can rack which may be readily converted from a single rack to a double rack.

Other objects of the invention will appear from the following description of one practical embodiment of the invention, when taken in conjunction with the drawings which accompany and form a part of this specification.

In the drawings:

Figure 1 is a side elevation of a double rack constructed in accordance with the present invention with two cans in the rack;

2

Figure 2 is a top plan view of the structure shown in Figure 1;

Figure 3 is a vertical section through one section of the rack and the can placed therein; and

Figure 4 is a perspective view of one section of the rack with the can lid in place and the lid partially raised.

The invention in general comprises a rack having an annular base member with brackets secured to the outside thereof at diametrically opposite points to receive and rigidly support a pair of vertical posts. Means for hingedly supporting a can lid is carried by one of the posts, and means for securing the lid in closed position is carried by the other post.

Referring to the drawings in detail, the base 1 may be simply a horizontally positioned ring or hoop-like member of such size as to snugly receive the bottom of a garbage, trash, or like can 2, of predetermined size. The base member is provided with a bottom 3 upon which the can rests to keep it from contacting the ground. The bottom is preferably of skeleton form, so that complete and rapid draining may be effected to prevent rusting of the bottom of the can. Brackets 4 and 5 are welded, riveted, or otherwise secured to the opposite sides of the annular base member 1. The brackets 4 and 5 are provided with threaded openings 6 and 7, extending completely through the brackets to receive the threaded lower ends of vertically positioned posts 8 and 9. The ends of the posts are screwed only part way into openings 6 and 7 in the brackets, so that, if desired, anchoring posts 10, shown in dotted lines, may be screwed in from the under side and imbedded in the ground or a cement foundation block, if such is used. The rack will have sufficient weight so that it cannot be easily overturned even if unanchored, and the use of the anchoring posts will be a matter of personal preference.

Brackets 4 and 5 are sufficiently long, and the openings 6 and 7 so placed in the brackets that posts 8 and 9 will rise well spaced from the widest diameter of the can 2, to permit easy removal of the can. It will be evident that both brackets may be of the type of bracket 4, where a rack for a single can is desired. Bracket 5 is for use on a double rack, and is considerably longer than bracket 4, and is symmetrical about the centrally positioned opening 6, providing means for attachment to a second annular base member 1.

A hinge block 11, having a threaded opening 12 in its under side is screwed onto the upper end of post 9. The upper face of block 11 slopes upwardly from its transverse center line toward its outer edges, forming inclined surfaces 12, the surfaces 12 being recessed near each outer edge 60 of the block to form seats 13, sufficiently deep to

receive the folded leaves of hinges 14, one leaf of each hinge being secured to its seat 13 by screws or other suitable means. Obviously, if only a single rack is desired, only one hinge is attached to the block, the other recess 13 being unused. The other leaf of each hinge 14 is secured to the end of a combination lid locking and brace member 15, which is in the form of a strap of flat metal stock bent to substantially conform to the cross-sectional contour of the can lid 16. The can lid is fastened to the member 15 by bolts or other easily applied fastening means 17. The member 15 serves to stiffen the lid to a great extent, and also secures the lid to the rack so that it cannot become lost. A handle 18 may be carried by the brace member 15, to facilitate raising and lowering the lid.

The outer end of the brace member 15 is bent to lie in a horizontal plane when the lid is in closed position, and a guide block 19 is fixed to the under side thereof. Guide block 19 has a tapered recess 20 extending vertically into its under side, which is adapted to seat on the tapered upper end 21 of the post 8. The size and position of the guide block 19 is such that it will strike the upper end of post 8 before the can lid strikes the upper side edges of the can if the lid is not centered above the can. This will prevent damage to the can and lid. If the lid in closing is but slightly off center, the recess in the guide block will engage the tapered end of post 8 and guide the lid to a proper seat. This will ensure the proper fitting of the lid during the life of the can.

Beyond guide block 19 the brace member 15 is bent to form a transverse recess at its outer end. A slot 22 extends inwardly from the end of the strip, dividing the end portion embracing the recess, into two hook-like elements 23, which serve as keepers for a spring tensioned locking device. Fixed to the post 8 is a U-shaped housing 24, having a pin 25 extending across its lower portion to form an anchor for one end of a coil spring 26. The upper end of the spring is connected to a link 27 which is provided with an eye to receive a handle 28. Handle 28 is preferably of rectangular form, having an offset on its lower side. The eye of link 27 engages the offset portion, and the shoulders 29, formed on either side of the offset will engage the hook elements 23 to tightly hold the lid in place on the can.

In use, the rack is placed in a selected spot, and if desired, anchored by the posts 10. A garbage or trash can is then placed in the rack, being seated within the annular base ring 1, upon the bottom members 3. The can lid 16 is next bolted to the brace member 15, and the rack is ready for service. The lid may be easily raised and lowered by grasping the handle 18, and when raised to the fullest extent with the leaves of the hinge closed, the lid will rest upon the inclined surface 12 of the hinge block, positioning the lid at an angle. To reach this position, the lid passes beyond a dead center position, thus throwing its weight upon the hinge block and becoming self-sustaining. This places the lid completely out of way of the can, so that the can may be removed from the rack without interference. As the lid is closed, the guide block 19 leads it to a proper seat, whereupon the locking handle 28 is pulled upward, extending the spring 26 until the link 27 may be slipped into the slot 22. The upward

pull on the locking handle is then released, allowing the spring to draw the shoulders 29 of the locking handle into the hook elements 23. The can is then safe from accidental removal of the lid.

While in the above there has been disclosed one practical embodiment of the invention it is to be understood that the precise embodiment shown and described is merely by way of example and not to be construed as limiting the scope of the appended claims.

What I claim as my invention is:

1. A rack for holding garbage, trash and like cans comprising, an annular recessed base member to receive and position a can and having portions offset therefrom, said offset portions having openings therein spaced from said annular recess, vertical posts fixed in said openings, a lid brace hingedly connected to one of said posts and adapted to seat upon another of said posts, said lid brace being an elongated member bent to substantially conform to the cross-sectional shape of a can lid to closely embrace said can lid and having means for attachment to said can lid said bent portion of said brace being so positioned between the ends of said brace that the can lid carried thereby will be in axial alignment with the recess in said base when said brace is seated upon said posts, means carried by said lid brace to guide said brace to its seat, complementary guide means carried by the post upon which the brace seats, and releasable means to hold said lid brace in seated position.

2. A rack for holding garbage, trash and like cans comprising, an annular recessed base member to receive and position a can and having portions offset therefrom, said offset portions having openings therein spaced from said annular recess, vertical posts fixed in said openings, a hinge block secured to the top of one of said posts, a lid brace hingedly connected to said hinge block and adapted to seat upon another of said posts, said lid brace being an elongated member bent to substantially conform to the cross-sectional shape of a can lid to closely embrace said can lid and having means for attachment to said can lid said bent portion of said brace being so positioned between the ends of said brace that the can lid carried thereby will be in axial alignment with the recess in said base when said brace is seated upon said posts, means carried by said lid brace to guide said brace to its seat, complementary guide means carried by the post upon which the brace seats, said hinge block having an inclined upper surface adjacent the hinge connection to said lid brace upon which said brace and lid may rest in an inclined beyond the vertical position when the brace is raised, and releasable means to hold said lid brace in seated position.

THOMAS NELSON ELLIOTT.
